UNITED STATES PATENT OFFICE.

AARON G. TURPEN, OF MODESTO, CALIFORNIA.

AUTOMATIC TRAIN-STOP.

1,141,023.

Specification of Letters Patent.

Patented May 25, 1915.

Application filed June 5, 1914. Serial No. 843,232.

To all whom it may concern:

Be it known that I, AARON G. TURPEN, a citizen of the United States, residing at Modesto, in the county of Stanislaus and 5 State of California, have invented new and useful Improvements in Automatic Train- Stops, of which the following is a specification.

This invention relates to improvements in 10 automatic train stopping apparatus and has particular reference to signal controlled apparatus of this character.

In carrying out the present invention, it 15 is my purpose to provide an automatic train stop which will be found especially useful in conjunction with the usual road signal system and whereby the brakes of a train or car as the case may be will be automatically applied in the event of such car or 20 train passing the danger signal.

It is also my purpose to provide an apparatus of the type set forth which will embrace the desired features of simplicity, efficiency and durability and which may be 25 installed and maintained at a minimum expense.

With the above and other objects in view, the invention consists in the construction, 30 combination and arrangement of parts hereinafter set forth in and falling within the scope of the claim.

In the accompanying drawings, Figure 1 is a fragmentary side elevation of the trackway showing the positions of the track instruments and semaphores controlling the same. Fig. 2 is a vertical sectional view through a track instrument. Fig. 3 is a diagrammatic view showing the circuit connection between the motor of the track instrument and the source of energy therefor. Fig. 4 is a diagrammatic view of the car carried stopping mechanism. Fig. 5 is a 40 sectional view through a detail thereof.

Referring now to the drawings in detail, 1 indicates a trackway. In the present instance, this trackway is divided into blocks and arranged adjacent to the entrance to each block is a semaphore 3 comprising a base 4, a standard 5 uprising from the base, and 5 a signal blade 6 pivoted upon the standard 5 adjacent to the upper end thereof and capable of movement to danger and clear positions. Also arranged at the entrance to each block is a track instrument 7, comprising, in the present instance, a casing 8

having an opening 9 formed in the top wall thereof. Journaled in horizontally alining bearings within the casing 8 and parallel with the lines of the rails of the trackway is a shaft 10 and fixed upon the shaft 10 is 60 a plate 11 capable of swinging movement and adapted to be projected out of the casing by way of the opening 9 in the top wall thereof when the shaft 10 is rotated in one direction. Disposed in proximity to the shaft 10 is an electric motor 12 having a bevel pinion 13 keyed upon the armature shaft thereof and meshing with a bevel gear 14 upon the end of the shaft 10. A coiled contractile spring 15 has one end secured 65 to the plate 11 and the opposite end fastened to the bottom wall of the casing 8 and acts to hold the plate 11 within the casing and to restore such plate to normal position succeeding the deenergization of the 70 motor 12. By means of this construction, it will be seen that when the motor 12 is energized the armature shaft will be rotated and motion transmitted to the shaft 10 through the medium of the bevel pinion 13 75 and the gear 14 thereby swinging the plate 11 out of the casing to active position against the action of the spring 15. On the other hand, when the motor is deenergized the spring 15 reacts to swing the plate 11 80 into the casing to inactive position. The electric motor 12 of each track instrument 85 is connected in an electric circuit 16 including a suitable source of energy as a battery 17 disposed within the base 4 of the adjacent semaphore, and a circuit closer 18 connected with the signal blade of the semaphore and adapted to close the circuit when the blade is swung to danger position and break the circuit when the blade goes to 90 clear. Thus, when the blade is moved to danger position the circuit 16 is closed and the motor 12 energized whereby the plate 11 is swung to active position as previously 95 described. In this form of my invention, 100 the car carried mechanism comprises an electric motor 19 connected in an electric circuit 20 including a suitable source of energy as a battery 21 and a switch 22 having the blade thereof connected with the upper 105 end of a rod 23 depending from the car and connected with a shoe 24 adapted to engage the upper edge of the plate 11 when the latter is active and the car passes the danger signal. Fixed upon the stem of the en- 110

gineer's brake valve is a gear 25 and meshing with the gear 25 is a pinion 26 carried by one end of a shaft 27, while upon the opposite end of the shaft 27 is a bevel gear 28 meshing with a pinion 29 keyed upon the armature shaft of the motor 19. In this instance, the pinion 26 is connected with the shaft 27 through the medium of a spring clutch as illustrated in Fig. 5 so that when 5 the shaft 27 is rotated under the action of the motor the gear 25 will be actuated to manipulate the engineer's brake valve to service position, while when the engineer's brake valve is manually restored to normal 10 position the shaft 27 will remain stationary, incident to the pinion 26 idling thereon.

In practice, assuming a track instrument to be active and a motor car to pass the danger signal the shoe 24 will ride upon the 15 upper edge of the plate 11 and actuate the rod 23 to close the switch 22 whereby the motor 19 will be energized. In the operation of the motor the shaft 27 is rotated with the effect to slowly manipulate the 20 engineer's brake valve to service position so that the brakes will be automatically ap- 25

plied and the car or train brought to a standstill.

I claim:

In automatic train stopping apparatus, 30 the combination with the engineer's brake valve, of a gear wheel secured to the stem of said valve, a shaft, a pinion on said shaft meshing with said gear wheel, an electric motor, a bevel gear on said shaft, a 35 bevel pinion on the shaft of said motor meshing with said bevel gear, an electric circuit for said motor, means for closing said circuit to rotate said shaft, and a spring clutch connection between said first pinion and said shaft whereby the pinion will actuate the engineer's brake valve in the movement of the shaft under the action of the motor and the pinion idle over the shaft in the reverse manual movement of 40 the engineer's brake valve.

In testimony whereof I affix my signature in presence of two witnesses:

AARON G. TURPEN.
